UNITED STATES PATENT OFFICE

2,048,220

VERTEBRAL ADJUSTING APPLIANCE

Daniel P. Redding, Kansas City, Mo.

Application August 6, 1934, Serial No. 738,671

16 Claims. (Cl. 128—69)

My invention relates to appliances for use by chiropractors in adjusting subluxations of the vertebrae. It is adapted for manual application to the patient by the practitioner.

5 The objects of my invention are:

1. To provide an improved process for adjusting vertebral subluxations;
2. To provide a light, simple, durable and easily operated and easily controlled appliance which can be utilized in giving chiropractic adjustments, of such a nature that force can be applied to the spine or to any given vertebra and readily directed in any desired direction, or in any desired "line of drive;"

15 3. To provide an appliance of the class described:

(a) By which the amount of force to be applied in any given instance can be regulated and predetermined by the operator with great accuracy;

20 (b) By which the same amount of force can be applied in successive adjustments;

(c) By which the amount of force applied in successive adjustments can be either increased or diminished from time to time;

25 (d) By which a uniform freedom of recoil can be assured;

(e) By which a uniformly short length of time during which the adjusting force is applied, can be assured;

30 (f) By which the amount of force to be applied in any given instance can be definitely predetermined independently of the physical or mental or nervous condition of the operator;

(g) By which the operator can be assured 35 against the application of excessive force or the application of insufficient force for a given adjustment;

(h) By which a chiropractor can administer 40 the desired adjustment even though lacking in the physical strength necessary to administer it entirely by the use of his own hands, and even though he lacks the experience, practice and physical training necessary to enable him to perform such an adjustment manually and without the use of an auxiliary appliance;

(i) By which a predetermined amount of torque can be applied in connection with the application of the necessary pressure or impact upon the spine or any particular vertebra thereof, in making a chiropractic adjustment;

(j) By which the torque may be applied in either direction in connection with the impact or pressure upon the vertebra in the course of adjustment;

(k) By which the amount of torque utilized in giving adjustments may be varied;

(l) By which the force applied in giving an adjustment may be localized and applied to a more restricted area than when such adjustments are administered by hand alone;

(m) By which resilient bodies of varying degrees of hardness and resiliency may be utilized for manual application to the subluxated spine or vertebrae for adjustment thereof;

(n) By which resilient bodies of varying sizes may be utilized for manual application to the subluxated spine or vertebrae for adjustment thereof.

I attain these objects by the means illustrated in the accompanying drawing, in which,—

Figure 1 is a longitudinal section of my appliance on the line 1—1 of Figure 2;

Figure 2 is a cross-section on the line 2—2 of Figure 1;

Figure 3 is an enlarged detail of the front end of my appliance;

Figure 4 is a detail view of the plunger, 8, showing it turned about a quarter of a revolution from the position shown in Figure 1 with a straight groove, 32, at the front thereof;

Figure 5 is a detail showing the sight, 1', formed therein.

For convenience I refer to the left of Figure 1 as the front and to the right of Figure 1 as the rear.

Similar numerals refer to similar parts throughout the several views.

My appliance comprises a barrel, 1, having a cylindrical cap, 2, threaded upon the front end thereof and a cylindrical cap, 25, threaded upon the rear end thereof.

A plunger, 6, is slidably mounted within the barrel the rear end of which projects into or through a bore formed in the prolonged end of the rear cap, 25. A head, 6', is formed at the front of the plunger, 6. An annular stop, 23, is seated in the barrel, 1, or may be formed integral therewith and a spacer, 24, is seated in the rear of the barrel between the stop 23, and the cap, 25.

An opening or sight, 1', is left in the side of the barrel, 1, a little in front of the trigger 12. The plunger, 6, is calibrated and has marked on the side thereof numerals, 1", which may be used to indicate a calibration thereof either in pounds or any other desired form. If desired, the calibration marks may be placed at the rear of the plunger, 6, so that they can be read from the portion of the plunger, 6, projecting to the rear of the barrel, when in charged position.

A compression spring, 7, is slidably mounted within the barrel, 1, and encircles the plunger, 6, throughout a considerable portion of its length. The size, power and resiliency of this spring may 5 be varied to suit the requirements of different sizes of instruments.

A secondary plunger, 8, is slidably mounted within a central bore formed in the cap, 2, and extends lengthwise thereof. A resilient head, 8', 10 of rubber or other suitable material, is mounted upon the rear end of the plunger, 8, adjacent a collar, 8'', which is mounted upon or formed integral with the plunger, 8.

The front end of the plunger, 8, is provided 15 with a collar, 5, formed integral therewith and upon the front end of said plunger and the collar, 5, a resilient head, 4, is mounted. This head, 4, is preferably made of rubber. A plurality of heads, 4, may be provided with each apparatus 20 of different sizes and different degrees of resilience and hardness and these heads are made readily removable so that they can be easily exchanged as required for different cases.

Spiral grooves, 31 and 31', are cut in the face 25 of the plunger, 8, and extend lengthwise thereof and one or more longitudinal grooves, 32, are formed in the face of the plunger, 8. A pin, 29, is mounted in a suitable bore extending into one 30 side of the cap, 2, and its inner end is adapted to seat in the grooves, 31 and 31', or 32.

A collar, 29', is rigidly secured to the pin, 29. A compression spring, 30, is united to the cap, 2, by set screws or other suitable means and has a fork which embraces the pin, 29, and bears 35 against the collar, 29', to hold the inner end of the pin, 29, in one of the grooves, and when so held, the pin, 29, will cause a turning or twisting motion of the plunger, 8, whenever it is moved longitudinally within the cap, 2.

40 When the pin, 29, is inserted in the straight groove, 32, it will prevent any turning or twisting motion of the plunger while moving longitudinally.

The grooves, 31 and 31', travel around the 45 plunger, 8, in opposite directions so that the groove, 31, in conjunction with the pin, 29, will cause the plunger to revolve in one direction and the groove, 31', in conjunction with the pin, 29, will cause the plunger, 8, to revolve in the opposite direction respectively when the plunger, 8, is driven longitudinally of the barrel, 1, and the cap, 2.

The plunger or rod, 6, has formed thereon a lock comprising a plurality of teeth, 6b, and upon 55 its opposite side is provided with a plurality of inclined notches, 6''.

A handle, 14, is united to the barrel, 1, near the rear thereof, with side plates, 15, secured thereto by pins, 27. The front of the upper portion 60 of the handle is slotted to receive a trigger, 12, the upper end of which may be pivoted upon pivots, 26, threaded into the handle and barrel.

65 A compression spring, 13, is mounted in the handle which bears against the lower portion of the trigger in a forward direction and against the handle in a rearward direction and is adapted to hold the trigger in the charged position. The trigger, 12, is provided with a catch, 12', 70 which projects into and fits against the rear walls of the notches, 6'', and acts to restrain the plunger, 6, against forward travel when in charged position. When the trigger is pulled manually, the catch, 12', is withdrawn from con-

tact with the notches, 6'', and the spring, 7, drives the plunger, 6, forward.

The handle, 14, is provided with an upward extension in which a pivot, 22, is secured and upon this pivot is mounted a gear wheel, 10, the teeth 5 of which correspond to the teeth, 6b, of the plunger, 6, the wheel, 10, being adapted to actuate the plunger to place same in the charged position and to be actuated by the plunger, 6, when traveling forward.

10 A charging lever, 9, has a fork, 9', at its lower end which straddles the gear wheel, 10, and is pivotally secured upon the pivot, 22. A detent, 28, is mounted upon or formed integral with the barrel, 1, having a small opening upon the rear 15 face thereof which is adapted to receive a ball, 16, carried by the charging lever, 9, and to retain the charging lever, 9, in its downward or latched position.

The ball, 16, is secured at the front or upper 20 end of the charging lever, 9, by a cap, 17, which is threaded upon the forward or upper end of the lever, 9, and a compression spring, 18, is mounted within a suitable bore formed in the free end of the charging lever, 9, and bears against 25 the ball, 16, so as to cause the ball to retain the charging lever in the position shown in dotted lines in Figure 1, with a light pressure which may be overcome manually by the operator when the forward end of the lever, 9, is pulled upwardly 30 or away from the barrel, 1.

A three-arm pawl, 11, is pivotally mounted 35 within the fork of the lever, 9, by a pivot pin or other suitable means, 21. A spring, 20, has one end secured to the lever, 9, by a pin, 20a. The free end of the spring, 20, bears against one arm of the pawl, 11, and tends to secure the pawl in engagement with the teeth of the gear wheel, 10.

The pawl, 11, is provided with an upwardly extending arm or finger which may readily be 40 pressed by the thumb of the operator and the pawl be thus disengaged from the gear wheel, 10.

The third arm or finger of the pawl, 11, is adapted to engage the upper surface of the barrel when the charging lever, 9, is returned to the 45 position shown in dotted lines in Figure 1 and to hold the pawl, 11, out of engagement with the teeth of the gear wheel, 10.

A collar, 8'', is formed near the rear end of the plunger, 8, which will contact with the cap, 2, 50 and act as a detent to prevent the plunger, 8, from being projected entirely out of the barrel, 1, and cap, 2.

In the operation of my device, the charging lever, 9, is raised from the horizontal to the 55 oblique position shown in Figure 1, and as it is raised, carries the pawl, 11, with it. The spring, 20, acting upon one arm of the pawl, causes the pawl to engage with the teeth of the gear wheel, 10. As the charging lever is then moved forwardly and downwardly, the gear wheel carries the plunger, 6, to the rear and the notches, 6'', are engaged by the catch, 12', of the trigger, 12, and the plunger, 6, is thus retained in its partially charged position. The lever, 9, may then 65 be again raised and lowered and the plunger, 6, moved still farther to the rear where it is again detained by the trigger and this operation repeated until the desired position of the plunger, 6, is reached.

70 The pawl, 11, is then released from the gear wheel by the thumb pressure upon the upwardly extending arm of the pawl, 11, and the charging lever locked in the position shown in dotted lines in Figure 1 parallel to the barrel.

The plunger, 6, is shown in its charged position in dotted lines, 6a, 6'a and 6''a. When the plunger, 6, has been locked in its charged position, the plunger, 8, is manually pushed to the rear so that the head, 8', comes into contact with the head of the plunger, 8, and the head, 4, is in the position shown in dotted lines as 4a.

The appliance is then placed in position relative to the patient so that the head, 4, is in contact with the patient's back in the desired position relative to the portion of the spine or vertebra to which the adjusting force is to be applied, the pin, 29, having been previously seated in one of the grooves, 31 or 31', so as to produce the desired torque or the pin, 29, may have been removed entirely so as to avoid the application of any torque.

The barrel is then carefully aligned in the desired direction in which it is desired to have the adjusting force applied. The appliance is then held firmly by the operator and the trigger pulled. When the trigger is pulled, the plunger, 6, will be forced by the spring, 7, forwardly with the force corresponding to the degree to which the spring, 7, has been compressed in the charging operation. The plunger, 6, transmits its force to the plunger, 8, and in turn to the head, 4, from which it is transmitted to the patient.

The spring, 7, bearing against the stop, 23, will naturally cause a recoil of the barrel, 1, as the plunger, 8, and head, 4, are pressed against the back of the patient. Any recoil movement of the barrel will tend to carry with it the plunger, 6, and thus leave a short space within which the plunger, 8, itself may recoil to the rear after the pressure of the plunger, 6, thereon has been withdrawn.

I prefer to proportion the parts of my apparatus so that the spring, 7, will not extend far enough at any time to hold the head of the plunger, 6, in contact with the head, 8', of the plunger 8, when in its forwardmost position so that there will normally be a certain distance in which the plunger, 8, is free to recoil. However, I do not limit my claims to an appliance of fixed size or proportions, but the various parts of my appliance may be varied to suit the requirements of different cases.

My process is carried out by the use of the apparatus just described and will be readily understood by those skilled in the chiropractic art.

It is a matter of common knowledge among chiropractors that different vertebral subluxations require different lines of drive of the force applied to correct them; also that some subluxations may require a certain amount of torque or twisting movement to the right and others may require a torque to the left.

For convenience and clearness in the claims, I have referred to the plunger or rod, 6, as the "driving rod" or "rod" and to the plunger or rod, 8, as the "plunger."

For convenience I shall refer to the direct force applied to the spine in adjusting a subluxation as the "drive" or "driving force" and to the rotary or twisting movement sometimes applied in giving such adjustments as the "torque", which may be either to the right or left as the case may be. I shall also refer to the direction in which the direct force is applied as the "line of drive."

It is a matter of common knowledge among chiropractors that the amount of force necessary to adjust subluxated vertebrae differs widely in different cases, depending somewhat upon

the age and muscular development of the patient, the nature, position and extent of the subluxation, the length of time which has elapsed since the subluxation occurred and other factors it is unnecessary to specify.

It is also a matter of common knowledge that it is important for chiropractor practitioner to develop a high degree of strength and agility in the muscles of his hands and arms to enable him to administer adjustments generally with the desired success.

It is well known that the correction of subluxations in many cases occurs during what is commonly known as the recoil rather than during the application of the driving force.

We find in practice that two forces are in concurrence, the invasionary force being delivered by the operator or the instrument and the resistance force being returned and coming from the object struck. The subluxation is not adjusted by the invasionary force alone, neither is the subluxation adjusted by the resistance force from within alone; but the adjustment of a subluxated vertebra takes place when the two forces come in contact each with the other; the body is driven away from and then recoils. It is during this recoil reaction upon the part of the body that the actual correct repositioning of the subluxated vertebra takes place.

In other words, there is a certain amount of resilience in the structures comprising the spinal column and when a portion of the spinal column is struck or subjected to a blow or to a sudden impact, these structures yield to the force of the blow or impact in proportion to the force applied, and as soon as the force of the blow or impact ceases or is removed, the natural resilience of the spinal structures causes a rebound or reaction which is commonly called a recoil. This recoil is an important element in accomplishing the return of the subluxated vertebra to its normal position.

These conditions render it necessary that any process of adjustment, to be successful, must involve the application of the proper or requisite amount of force or direct drive upon the proper portion of the spine and this force must be directed in the proper direction. Such process must also permit full freedom of recoil or reaction.

My apparatus provides means by which the direction of the drive can be accurately controlled. The driving rod slides longitudinally of the barrel. It is obvious then that if the contact head, 4, be placed in contact with the back of a patient at the desired point, the barrel may be inclined so that it points in the direction in which it is desired to have the force applied and as the trigger is pulled and the driving rod, 6, moves forward in the barrel, the driving force will necessarily be applied in the direction in which the barrel is pointed.

My apparatus also provides means by which the amount of force to be applied by direct drive can be regulated or predetermined. The length of the driving rod, 6, and of the rack formed by the teeth, 6b, is such that the driving rod may be retracted to various degrees measured by the notches, 6''. As the rod, 6, is retracted, its head exerts pressure upon the coiled spring, 7, and compresses it, the coiled spring, 7, being made of suitable size to afford the maximum desired amount of force when the driving rod is retracted to the last notch, 6'', and to afford inter-

mediate degrees of force for the intermediate notches.

The spring, 7, and the travel of the driving rod, 6, are intended to be so proportioned that when the rod is fully retracted, it will, when released by the trigger, 12, strike the head, 8', with sufficient force to compel the head, 4, to deliver an impact against the body proportional to the greatest degree of force which a chiropractor is called upon to deliver manually in performing an adjustment in the ordinary way. The intermediate degrees of force deliverable by the driving rod, 6, are intended to be proportional to the varying degrees of force which chiropractors have found it necessary to utilize in giving adjustments manually.

It is obvious that my appliance may be made so as to be able to deliver an impact of greater force than could be delivered manually in the ordinary way, and where a chiropractor has insufficient strength to apply the desired amount of force, my appliance will afford a ready means of applying a greater force than he can do by the use of his hands alone.

Likewise, it has been found that many persons do not possess the requisite agility—that is, they do not have sufficiently rapid control of their muscular movements—to deliver a sudden impact by hand and then withdraw the hand with sufficient rapidity to permit a free recoil of the patient.

My apparatus obviously can be depended upon to permit a sudden recoil because the action of the spring, 7, will naturally cause certain inertia in the driving rod, 6, which will tend to carry it somewhat beyond the normal length of the spring, 7, and as the spring pressure is thus removed from it, the driving rod, 6, will be free to return as the plunger, 8, is driven backward by the recoil of the patient acting upon the resilient head, 4. The resilience of the head, 4, will also assist in this recoil movement.

Instead of the torque or twisting movement of the hand or hands of the operator in adjusting, my apparatus provides for a torque or twisting movement of the head, 4, which takes the place of the torque delivered by the operator directly and may be either increased or diminished by the operator by turning the handle, 14, either to the right or left as may be desired at the time the trigger is pulled.

I do not limit my claims to the precise form of apparatus here shown nor to the exact description of my process above set out, but claim broadly both apparatus and process and their equivalents.

I claim:

1. In a vertebral adjusting appliance, a barrel, a pistol grip united thereto, a driving rod slidably mounted in the barrel, a plunger mounted in the front end of the barrel, a head united to the front end of the plunger, a helical spring mounted within the barrel adapted to exert pressure rearwardly against the barrel and forwardly against the driving rod, a trigger mounted in the grip having a catch formed integral therewith, notches formed in the one side of the driving rod adapted to be engaged by the catch of the trigger by which the rod can be retained in charged position and released when the trigger is pulled, a setting lever one end of which is forked, having its forked end pivotally united to the barrel, a slot in the upper face of the barrel adjacent to said fork, a toothed wheel revolvably mounted within the fork upon the setting lever pivot, a pawl pivoted in the fork of the setting lever adapted to engage the teeth of the wheel and to actuate

same when the setting lever is moved forwardly from its vertical to a horizontal position, spring-actuated means for holding the pawl in engagement with the teeth of the wheel, and manually operable means for releasing the pawl.

2. In a vertebral adjusting appliance, a barrel, a grip united thereto, a driving rod slidably mounted in the barrel, a plunger mounted in the front end of the barrel, a head united to the front end of the plunger, resilient means mounted within the barrel adapted, when in charged position, to exert pressure rearwardly against the barrel and forwardly against the driving rod, a trigger mounted in the grip, means by which the rod can be retained in charged position and released when the trigger is pulled, a setting lever one end of which is forked, having its forked end pivotally united to the barrel, a slot in the upper face of the barrel adjacent to said fork, a toothed wheel revolvably mounted within the fork upon the setting lever pivot, a pawl pivoted in the fork of the setting lever adapted to engage the teeth of the wheel and to actuate same when the setting lever is moved forwardly from its vertical to a horizontal position, spring-actuated means for holding the pawl in engagement with the teeth of the wheel, and manually operable means for releasing the pawl.

3. In a vertebral adjusting appliance, a barrel, a pistol grip united thereto, a driving rod slidably mounted in the barrel, a plunger mounted in the front end of the barrel, a head united to the front end of the plunger, a helical spring mounted within the barrel adapted to exert pressure rearwardly against the barrel and forwardly against the driving rod, a trigger mounted in the grip having a catch formed integral therewith, notches formed in the one side of the driving rod adapted to be engaged by the catch of the trigger by which the rod can be retained in charged position and released when the trigger is pulled, and manually operable means united to the barrel by which the driving rod can be placed in charged position and so held until released by pulling the trigger.

4. In a vertical adjusting appliance, a barrel, a grip united thereto, a driving rod slidably mounted in the barrel, a plunger mounted in the front end of the barrel, a head united to the front end of the plunger, resilient means mounted within the barrel adapted, when in charged position, to exert pressure rearwardly against the barrel and forwardly against the driving rod, a trigger mounted in the grip, means by which the rod can be retained in charged position and released when the trigger is pulled, and manually operable means united to the barrel by which the driving rod can be placed in charged position and so held until released by pulling the trigger.

5. In a vertebral adjusting appliance, a barrel, a grip united thereto, a driving rod slidably mounted in the barrel, a plunger mounted in the front end of the barrel, a head united to the front end of the plunger, resilient means mounted within the barrel adapted, when in charged position, to exert pressure rearwardly against the barrel and forwardly against the driving rod, a trigger mounted in the grip, adjustable means by which the rod can be retained in charged position and released when the trigger is pulled, a setting lever one end of which is forked, having its forked end pivotally united to the barrel, a slot in the upper face of the barrel adjacent to said fork, a toothed wheel revolvably mounted within the fork upon the setting lever pivot, a pawl pivoted in the fork of the setting lever adapted to engage the teeth of the wheel and to actuate

in the fork of the setting lever adapted to engage the teeth of the wheel and to actuate same when the setting lever is moved forwardly from its vertical to a horizontal position, spring-actuated means for holding the pawl in engagement with the teeth of the wheel, and manually operable means for releasing the pawl.

6. In a vertebral adjusting appliance, a barrel, a grip united thereto, a driving rod slidably mounted in the barrel, a plunger mounted in the front end of the barrel, a head united to the front end of the plunger, resilient means mounted within the barrel adapted, when in charged position, to exert pressure rearwardly against the barrel and forwardly against the driving rod, a trigger mounted in the grip, adjustable means by which the rod can be retained in charged position and released when the trigger is pulled, and manually operable means united to the barrel by which the driving rod can be placed in charged position and so held until released by pulling the trigger.

7. In a vertebral adjusting appliance, a barrel, a pistol grip united thereto, a driving rod slidably mounted in the barrel, a plunger mounted in the front end of the barrel adapted to be actuated by the driving rod when released from charged position, a resilient head united to the front end of the plunger, a helical spring mounted within the barrel adapted to exert pressure rearwardly against the barrel and forwardly against the driving rod, a trigger mounted in the grip, a catch formed on the trigger, notches formed in one side of the driving rod adapted to be engaged by the catch of the trigger by which the rod can be retained in charged position and released when the trigger is pulled, and manually operable means united to the barrel by which the driving rod can be placed in charged position and so held until released by pulling the trigger.

8. In a vertebral adjusting appliance, a barrel, a pistol grip united thereto, a driving rod slidably mounted in the barrel, a plunger mounted in the front end of the barrel adapted to be actuated by the driving rod when released from charged position, resilient heads united to both ends of the plunger, a helical spring mounted within the barrel adapted to exert pressure rearwardly against the barrel and forwardly against the driving rod, a trigger mounted in the grip, a catch formed on the trigger, notches formed in one side of the driving rod adapted to be engaged by the catch of the trigger by which the rod can be retained in charged position and released when the trigger is pulled, and manually operable means united to the barrel by which the driving rod can be placed in charged position and so held until released by pulling the trigger.

9. In a vertebral adjusting appliance, a barrel, a grip united thereto, a driving rod slidably mounted in the barrel, a plunger mounted in the front end of the barrel adapted to be actuated by the driving rod when released from charged position, heads united to both ends of the plunger, means mounted within the barrel adapted, when in charged position, to exert pressure rearwardly against the barrel and forwardly against the driving rod, a trigger mounted in the grip, means by which the rod can be retained in charged position and released when the trigger is pulled, and manually operable means united to the barrel by which the driving rod can be placed in charged position and so held until released by pulling the trigger.

10. In a vertebral adjusting appliance, a barrel,

a cylindrical cap threaded upon the front end thereof, a pistol grip united to the barrel, a driving rod slidably mounted in the barrel, a plunger slidably mounted in the front end of the barrel and the cylindrical cap and having oppositely directed spiral grooves cut in the periphery thereof, a removable pin seated in the cap with its inner end adapted to seat in either of said grooves and cause the plunger to rotate as it moves lengthwise in the cap, a resilient head united to the front end of the plunger, a spring mounted within the barrel adapted to exert pressure rearwardly against the barrel and forwardly against the driving rod and cause the driving rod to actuate the plunger when released from charged position, a trigger mounted in the grip, notches formed in one side of the driving rod adapted to be engaged by the catch of the trigger by which the rod can be retained in charged position and released when the trigger is pulled, and manually operable means united to the barrel by which the driving rod can be placed in charged position and so held until released by pulling the trigger.

11. In a vertebral adjusting appliance, a barrel, a cylindrical cap threaded upon the front end thereof, a pistol grip united to the barrel, a driving rod slidably mounted in the barrel, a plunger slidably mounted in the front end of the barrel and the cylindrical cap and having oppositely directed spiral grooves cut in the periphery thereof, a removable pin seated in the cap with its inner end adapted to seat in either of said grooves and cause the plunger to rotate as it moves lengthwise in the cap, a resilient head united to the front end of the plunger, resilient means within the barrel adapted to exert pressure rearwardly against the barrel and forwardly against the driving rod and cause the driving rod to actuate the plunger when released from charged position, a trigger mounted in the grip, a catch formed on the trigger, notches formed in one side of the driving rod adapted to be engaged by the catch of the trigger by which the rod can be retained in charged position and released when the trigger is pulled, and manually operable means united to the barrel by which the driving rod can be placed in charged position and so held until released by pulling the trigger.

12. In a vertebral adjusting appliance, a barrel, a cylindrical cap threaded upon the front end thereof, a grip united to the barrel, a driving rod slidably mounted in the front end of the barrel, a plunger slidably mounted in the front end of the barrel, a cap adapted to be actuated by the driving rod when released from charged position, the cylindrical cap having oppositely directed spiral grooves cut in the periphery thereof, a removable pin seated in the cap with its inner end adapted to seat in either of said grooves and cause the plunger to rotate as it moves lengthwise in the cap, a resilient head united to the front end of the plunger, resilient means within the barrel adapted to exert pressure rearwardly against the barrel and forwardly against the driving rod and cause the driving rod to actuate the plunger when released from charged position, and means adapted to detain the rod in charged position and to suddenly release it therefrom.

13. The process of adjusting a subluxated vertebra which consists of manually applying thereto a resilient pressure head, and mechanically causing the resilient head to rapidly exert a predetermined pressure upon a single vertebra continuing through a predetermined direction of

travel, which pressure is automatically instantly released and the pressure head withdrawn automatically when the predetermined travel has been completed.

14. The process of adjusting subluxated vertebrae which consists of manually applying there-to a resilient pressure head, and mechanically causing the resilient head to rapidly exert a pre-determined pressure upon a single vertebra causing the vertebra to travel through a predetermined direction and distance, which pressure is automatically instantly released when the predetermined travel has been completed, and the pressure head automatically withdrawn with sufficient rapidity to avoid any interference with the reflex movement of the vertebra.

15. The process of adjusting subluxated vertebrae which consists of manually applying there-to a resilient pressure head, and mechanically causing the resilient head to rapidly exert a pre-

determined pressure upon a single vertebra causing it to travel through a predetermined distance and direction, which pressure is automatically instantly released when the predetermined travel has been completed and the pressure head withdrawn with sufficient rapidity to avoid any interference with the natural return of the vertebra to its normal position.

16. The process of adjusting a subluxated vertebra which consists of manually applying there-to a resilient pressure head, and mechanically causing the resilient head to rapidly exert a pre-determined pressure upon a single vertebra continuing through a predetermined direction and length of travel, including travel forwardly and with a torque or twisting movement, which pressure is automatically instantly released and the pressure head withdrawn automatically when the predetermined travel has been completed.

DANIEL P. REDDING. 20
